TEETER-TYPE MATERIAL HANDLING TOY

Francis Harvey Stevens, Hamilton, Ontario,
Canada

Application January 29, 1948; Serial No. 5,092

2 Claims. (Cl. 46—41)

1 The present invention relates to a novel and improved teeter-type material handling toy and the purpose of the invention is to provide a simple juvenile amusement device wherein the teeter is in the form of a track and the material is handled in a rollable dump cart.

One object of the invention has to do with the adoption and use of an elongated track which is provided intermediate its ends with a roller-equipped prop and which parts combine to provide a novel teeter for the dump cart.

Another object of the invention appertains to a teeter in the form of a track, the latter having dump cart stops at opposite ends, the dump cart being provided with a trigger which is hand set and normally holds the material handling receptacle upright, the trigger being operated when it comes into contact with one of the stops, whereby said receptacle is released and tipped to the side for automatic dumping purposes.

Other objects and advantages will become more readily apparent from the following description and the accompanying illustrative drawings.

In the drawings, wherein like numerals are employed to designate like parts throughout the views:

Figure 1 is a side elevational view of a dump cart equipped teeter toy constructed in accordance with the present invention;

Figure 2 is an enlarged vertical cross section on the line 2—2 of Figure 1, looking in the direction of the arrows;

Figure 3 is a similar sectional view on the line 3—3 of Figure 1, looking in the direction of the arrows;

Figure 4 is an enlarged view observing the structure of Figure 1 in a direction from right to left;

Figure 5 is a fragmentary view on an enlarged scale taken on the horizontal line 5—5 of Figure 1, looking in the direction of the arrows.

Referring now to the drawings by reference numerals and lead lines, the teeter takes the form of a horizontally elongated track structure which is denoted, in a unitary structural sense, by the numeral 6. It comprises a pair of spaced parallel channel-shaped members or track rails 7 and 8 connected at the left-hand ends with an upstanding spacing and reinforcing block 9. This block serves as a bumper, in a manner to be hereinafter clarified. A similar block 10 is mounted between the opposite end portions of the track rails and this serves not only as a bumper but is provided with a hand grip, in the form of a knob 11 and the latter is used for tilting the teeter by

hand and starting the material handling dump vehicle 12 from a loading to an unloading position. The track means or structure also includes cross-pieces 13 which serve as spacers and stabilizers. Then, there is a centrally arranged prop 14 which comprises legs 15 attached rigidly to the intermediate portions of the track rails, said legs having a fulcruming and transporting roller 16 between their lower end portions. It is obvious, therefore, that the handle 11 may be used to trundle the track means from place to place, and that the prop and roller arrangement serve as a rocking post on which the track means teeters.

Taking up now the construction of the material handling and dump vehicle or toy 12, it will be seen in Figure 2 that this comprises a frame 17 which is of sheet metal and channel-shaped in cross sectional form and provided with depending walls 18 carrying outstanding assembling and guard flanges 19. These flanges interlock with the top flanges on the track rails and assist in holding the vehicle on said track flanges. It will be noted, in this connection, that there is an axle at 20 and it carries flanged wheels 21 and the co-acting wheel flanges and track and guard flanges serve to assemble the parts in an obvious manner. That is to say, the vehicle is safely clamped on the track means and at the same time is permitted to roll freely back and forth by the wheel means provided. The frame structure carries uprights 22 and these serve to accommodate the V-shaped material receiving and dump receptacle 23. The ends of the latter are pivoted as at 24 on the uprights and the pivot points have a low center of gravity, as is obvious. The left-hand end wall 25 of the receptacle is provided with a keeper notch 26 to accommodate a detent 27 on a trigger or latch. The latch is pivoted on an adaptor bracket 28 and has a lateral trip 29 which protrudes beyond the adjacent end portions of the vehicle frame 17. The latch or trigger means is set by hand when the vehicle is at the right in Figure 1 at which time it rests against the abutment or bumper 10. In this position the receptacle is loaded with sand or other material to be handled and dumped. The receptacle is then upright. However, by catching hold of the handle 11 and tilting the right-hand end of the track means up, the opposite end goes down and the vehicle rolls by gravity down the track until the trip 29 comes into releasing contact with the bumper 9. Then, with the trigger released the receptacle 23 is permitted to tilt to either one side

in the latter, to tilt sidewise to a load dumping position.

2. A manually actuatable table-type toy of the class described comprising a pair of relatively short rigid spaced parallel legs constituting a prop, a single trundling and fulcruming roller mounted for idling between the lower end portions of said legs, a hand shifted and tilttable teeter at right angles to said prop and embodying spaced parallel tracks disposed at right angles to and rigidly mounted between the upper end portions of said legs, a pair of bumpers secured to opposite end portions of said teeter rising vertically therefrom, one of said bumpers having an exteriorly disposed outstanding hand-grip, a wheel-equipped carriage slidably keyed for shiftable movements back and forth on said tracks, said carriage being provided with uprights, a loose material receiving, transporting and dumping receptacle hingedly suspended between said uprights and tilttable sidewise for purposes of dumping a load which is placed in the receptacle, a trigger pivotally mounted on said carriage, said receptacle having a keeper notch and said trigger having a detent fitting releasably into said notch to hold the receptacle normally upright and fixed in relation to and above the carriage, and said trigger also having a trip engageable with one of said bumpers for purposes of automatically releasing the detent and allowing the receptacle to swing over to one side for dumping its load.
